UNITED STATES PATENT OFFICE.

JUSTUS R. KINNEY, OF DORCHESTER, MASSACHUSETTS.

STARTING DEVICE FOR MOTOR-CARS.

1,082,595.

Specification of Letters Patent. Patented Dec. 30, 1913.

Application filed June 16, 1911. Serial No. 633,902.

To all whom it may concern:

Be it known that I, JUSTUS R. KINNEY, a citizen of the United States of America, and a resident of Dorchester, in the county of 5 Suffolk and State of Massachusetts, have invented certain new and useful Improvements in Starting Devices for Motor-Cars, of which the following is a specification.

This invention relates to starting devices 10 and particularly to starting devices which are used in connection with motor cars, the object of the present invention being to provide a device which may be actuated by compressed air or other fluid to cause an initial 15 rotation to the engine shaft, thus dispensing with the usual cranking, and then actuating it by compressed air or other fluid to return it to its normal position.

The invention consists in providing a supplemental shaft in alignment with the engine 20 shaft, which supplemental shaft is provided with a piston secured thereto reciprocable in a piston chamber and normally closing the passage to another chamber in which is positioned a radial blade secured to said supplemental shaft, said piston chamber being provided with means for admitting thereto compressed air or other fluid to move said 25 piston with its shaft endwise so that said shaft will engage the engine shaft and in so doing uncover the passage between said chambers and admit the compressed air or other fluid to the other chamber against said radial blade and cause an oscillation of 30 said shaft, thereby imparting to the engine shaft an initial rotation.

The invention consists further in mechanism for reciprocating and oscillating said 40 actuating shaft by means of fluid pressure under the control of the chauffeur, and for returning said shaft to its normal position by means of fluid pressure after an initial rotation has been imparted to the engine shaft.

The invention further consists in certain 45 novel features of construction and arrangement of parts which will be readily understood by reference to the description of the drawings and to the claims hereinafter given.

The invention as herein shown and described contains many features shown and described in another application of mine 50 filed May 31, 1911, Serial No. 630,537.

Of the drawings: Figure 1 represents a

section of a starting device embodying the features of the present invention, showing a clutch mechanism in elevation. Fig. 2 is a section of the same, the cutting plane being 60 on line 2—2 on Fig. 1, showing in elevation a portion of a compressed air tank and the pipes leading therefrom to the starting device. Fig. 3 is a section of the same, the cutting plane being on line 3—3 on Fig. 1. 65 Fig. 4 is a similar section of the controlling valves, showing said valves in position to start the device. Fig. 5 is a similar section, showing the valves in position to return the movable parts of the device to their normal 70 position. Fig. 6 represents a partial transverse section of the starting device, the cutting plane being on line 6 on Fig. 2; and Fig. 7 represents a partial transverse section of the same, the cutting plane being on line 75 7 on Fig. 2.

Similar characters designate like parts throughout the several figures of the drawings.

In the drawings, 10 represents a cup-shaped member provided with a cylindrical chamber 11, said cup-shaped member 10 being secured to a rear plate 13 by means of a plurality of bolts 14 passing through a flange 15 formed upon said cup-shaped member. The rear plate 13 is secured in a fixed position in any well-known manner, as, for instance, by means of screws engaging the threaded openings 16 in the lugs 17 80 formed upon said rear plate 13. An actuating shaft 18, mounted in suitable bearings formed in the said cup-shaped member 10 and said rear plate 13, is positioned within the center of said chamber 11. The outer end of said actuating shaft 18 is squared as indicated at 19 to receive a crank whereby the shaft 18 may be actuated in the usual manner when desired. The opposite end of 85 said shaft 18 has secured thereto a clutch member 20 and in alignment with said shaft 18 is an engine shaft 21 having secured to its end a coacting clutch member 22. These clutch members 20 and 22 are normally separated by means of a spring 23 acting upon one face of a piston 24 secured to or formed upon the shaft 18 and mounted in a cylindrical chamber 25 formed in the back plate 13, said piston chamber being preferably of less diameter than the chamber 11. 90

The forward movement of the piston 24, by the action thereon of the spring 23, is 100 105 110

limited by the hub of the clutch member 20 contacting with the closing cap 26 of the chamber 25 so that a compartment 27 is always left between the forward face of the 5 piston 24 and the inner end of the piston chamber 25. Communicating with the compartment 27 is a passage 28 formed in the back plate 13, from the outer end of which extends a supply pipe 29 communicating 10 with the compressed air tank 30. At a suitable point in the line of pipe 29 so that it is readily accessible to the chauffeur is a three-way valve 31, which is of any well-known construction, and is normally closed. Extending from the compartment 27 is another 15 passage 32 smaller than the passage 28, this passage 32 communicating through an opening 33 with the chamber 11.

Within the chamber 11 and keyed to the 20 shaft 18 in such a manner as to permit a reciprocating movement of said shaft, is a piston member 34, the opposite faces of which bear respectively against the inner faces of the cup-shaped member 10 and the 25 rear plate 13. Secured to or formed upon the piston member 34 is a segmental blade 35, the outer wall of which contacts with the cylindrical inner wall of the chamber 11. Secured to the cup-shaped member by means 30 of bolts 36 and by means of a bolt 37 extending through both said cup-shaped member 10 and the rear plate 13, is a segmental abutment 38, the inner wall of which contacts with the periphery of the piston member 34. The uncovered radial walls of the abutment 38 are provided with buffers 39 and 40 of rubber or any other suitable resilient material. The buffer 39 extends sufficiently beyond the face of the abutment 38 10 to prevent the opening 33 being closed at any time when the blade 35 is in its normal position, as indicated in Fig. 2 of the drawings. A branch pipe 41 leads from the supply pipe 29 to the chamber 11 on the opposite side of the abutment 38 from the opening 33. In this line of pipe 41 is a valve 42 normally closed to prevent the passage of the compressed air from the tank 30 into the chamber 11. This valve 42 like the valve 31 15 is a three-way valve, and both of these valves in their normal position are open to the atmosphere. The piston 24 has secured thereto a packing member 43 which normally covers the mouth of the passage 32 so 20 that compressed air or other fluid is prevented from entering said passage from the piston chamber 27 until the piston 24 has been moved endwise toward the engine shaft 21 against the tension of the spring 23. 25 The operation of the invention is as follows: The various movable parts of the device are normally in the positions shown in Figs. 1 and 2 of the drawings. The supply tank 30 is normally filled with air or other

fluid under pressure, while both valves 31 and 42 are in positions to prevent the passage of the compressed air from the supply tank 30 through the pipes 29 and 41 into the interior of the starting device. When it is desired to impart a rotary movement to the 50 engine shaft 21 to start the engine, the chauffeur opens the valve 31, permitting the air or other fluid contained within the tank 30 to pass through the pipe 29 into the compartment 27, the passage 32 being closed by the packing 43 upon or secured to the face of the piston 24. The admission of the compressed air into the chamber 27 acting against the face of the piston 24 causes said piston and the shaft 18 on which it is mounted to be moved toward the engine shaft 21 sufficiently to permit the clutch members 22 to engage. This movement of the piston 24 against the tension of the spring 23 will uncover the passage 32 by the 55 time the clutch members 20 and 22 have engaged one another and the compressed air being admitted through the pipe 29 and passage 28 into the chamber 27 will then flow through the passage 32 and the opening 33 into the chamber 11 between the abutment 38 and the radial blade 35. The action of the compressed air upon said blade will cause it to be moved in the direction of the arrow α on Fig. 2 until it strikes the yielding buffer 40, which buffer will limit its movement in that direction. This movement of the blade 35, secured as it is to the piston member 34, keyed to the shaft 18, will cause an oscillation of this shaft, and, through the 60 clutch members 20 and 22, impart an initial rotation to the engine shaft. As soon as the engine has been started in this manner, the valve 31 is then moved into the position shown in Fig. 4 of the drawings, thereby preventing the further admission of compressed air to the chamber 27, but permitting any compressed air which remains therein to pass therefrom through the passage 28 and pipe 29 to the outlet 44 in the 65 valve casing. The valve 42 is then moved into the position indicated in Fig. 4 of the drawings, thereby permitting the compressed air from the tank 30 to pass through the pipe 41 into the chamber 11 in the rear of the blade 35, said compressed air acting on said blade to return it to its normal position, as indicated in Fig. 1 of the drawings, any air in advance of the blade, while the shaft 18 is reversely rotated being permitted 70 to pass outwardly from the chamber 11 through the opening 33, passage 32, into the chamber 27, and then therefrom through the passage 28 and pipe 29, as heretofore described. The spring 23 will return the piston 24 to its normal position and the starting device will then be in condition to repeat this operation.

It is believed that the operation and many advantages of the invention will be thoroughly understood from the foregoing.

Having thus described my invention, I claim:

1. In a device of the class described, the combination of two normally separated alined shafts provided with means forming a temporary connection for the same; a casing having two chambers therein connected by a fluid passage and provided with bearings for one of said shafts; a reciprocating piston on the latter shaft in one of said chambers and normally closing said passage; means for supplying fluid pressure to said piston to cause a reciprocation of said shaft to uncover said passage and connect said alined shafts; and an oscillating blade in the other chamber secured to said reciprocating shaft and adapted to be subjected to the pressure of the fluid entering said chamber through said passage.

2. In a device of the class described, the combination of two normally separated alined shafts provided with means forming a temporary connection for the same; a casing having two chambers connected by a fluid passage and provided with bearings for one of said shafts; a reciprocating piston on the latter shaft in one of said chambers and normally closing said passage; means for supplying fluid pressure to said piston to cause a reciprocation of said shaft to uncover said passage and connect said alined shafts; an oscillating blade in the other chamber secured to said reciprocating shaft and adapted to be subjected to the pressure of the fluid entering said chamber through said passage; and means in the path of said blade to limit its rotary movement.

3. In a device of the class described, the combination of two normally separated alined shafts provided with means forming a temporary connection for the same; a casing having two chambers therein connected by a fluid passage and provided with bearings for one of said shafts; a reciprocating piston on the latter shaft in one of said chambers and normally closing said passage; a tank adapted to contain fluid under pressure; means for admitting a portion of said fluid to said piston chamber to cause a reciprocation of said shaft to uncover said passage and connect said alined shafts; an oscillating blade in the other chamber secured to said reciprocating shaft and adapted to be subjected to the pressure of the fluid entering said chamber through said passage; a spring for moving said reciprocating shaft to disconnect it from its companion shaft; and means connected to said tank for subsequently reversely rotating said reciprocating shaft to its normal position.

4. In a device of the class described, the

combination of two normally separated alined shafts provided with means forming a temporary connection for the same; a casing having two chambers therein connected by a fluid passage and provided with bearings for one of said shafts; a reciprocating piston on the latter shaft in one of said chambers and normally closing said passage; a tank adapted to contain fluid under pressure; means for admitting a portion of said fluid to said piston chamber to cause a reciprocation of said shaft to uncover said passage and connect said alined shafts; an oscillating blade in the other chamber secured to said reciprocating shaft and adapted to be subjected to the pressure of the fluid entering said chamber through said passage; and means connected to said tank for subjecting said blade at the extreme of its movement to fluid pressure to return it to its normal position.

5. In a device of the class described, the combination of two alined shafts; a clutch mechanism interposed between the opposed ends of said shafts; a casing having a chamber and an outlet passage therefrom; a piston on one of said shafts normally positioned in said chamber and closing said outlet passage but adapted to be moved in said chamber to uncover said passage and connect said clutch mechanism; a spring acting on said piston to retain it in its normal position; a blade on said reciprocating shaft; and means for supplying fluid through said passage to act on said blade and cause a rotary movement thereof.

6. In a device of the class described, the combination of two alined shafts; a clutch mechanism interposed between the opposed ends of said shafts; a piston on one of said shafts adapted to be acted upon to cause end movement to said shaft and the engagement of said clutch mechanism; a spring acting thereon to retain said clutch mechanism in inoperative position; a casing having a chamber in which said piston is positioned and an outlet passage therefrom normally closed by said piston, a blade on said reciprocating shaft; means for supplying fluid through said passage to act on said blade and cause a rotary movement thereof; and means for limiting said rotary movement.

7. In a device of the class described, the combination of two alined shafts; a clutch mechanism interposed between the opposed ends of said shafts; a piston on one of said shafts adapted to be acted upon to cause end movement to said shaft and the engagement of said clutch mechanism; a spring acting thereon to retain said clutch mechanism in inoperative position; a casing having a chamber in which said piston is positioned and an outlet passage therefrom normally

- closed by said piston; a blade on said reciprocating shaft; a storage tank for compressed fluid, means for admitting a portion of said fluid through said passage to act on said blade and cause a rotary movement thereof; and means connected to said tank for subjecting the opposite face of said blade to fluid pressure to cause it to return to its normal position.
8. In a device of the class described, the combination of two alined shafts; a clutch mechanism interposed between the opposed ends of said shafts; a piston on one of said shafts adapted to be acted upon to cause end movement to said shaft and the engagement of said clutch mechanism; a spring acting thereon to retain said clutch mechanism in inoperative position; a radial blade on said piston shaft; a storage tank for compressed fluid; means for subjecting said piston to fluid pressure to cause said clutch mechanism to be engaged and then subjecting said blade to the same fluid pressure from said tank to impart a rotary movement to said shaft; and means connected to said tank for subjecting the opposite face of said blade to fluid pressure to return it to its normal position.
9. In a device of the class described, the combination of two alined shafts; a clutch mechanism interposed between the opposed ends of said shafts; a fixed casing provided with two cylindrical chambers of different diameters connected by a fluid passage; a piston secured to one of said shafts and positioned in the smaller chamber; a spring acting upon one face of said piston; a storage tank for compressed fluid; means for admitting a portion of said fluid to said piston chamber to act upon the opposite face of said piston; a radial blade on said piston shaft positioned in said larger chamber adapted to be actuated by the inflow of fluid from said smaller chamber into said larger chamber to rotate said shaft; and means connected to said tank for subjecting the opposite face of said blade to fluid pressure to return said blade to its normal position.
10. In a device of the class described, the combination of two alined shafts; a clutch mechanism interposed between the opposed ends of said shafts; a fixed casing provided with two cylindrical chambers of different diameters connected by a fluid passage; a piston secured to one of said shafts and positioned in the smaller chamber; a spring acting upon one face of said piston; a storage tank for compressed fluid; means for admitting a portion of said fluid to said piston chamber to act upon the opposite face thereof; a radial blade on said piston shaft adapted to be actuated by the inflow of fluid from said smaller chamber into said larger chamber to rotate said shaft; an abutment in said

larger chamber to limit the movement of said blade in either direction; and means connected to said tank for introducing fluid between said abutment and said blade when at the extreme of its forward movement to return it to its normal position.

11. In a device of the class described, the combination of two normally separated alined shafts provided with means forming a temporary connection for the same, one of which shafts is adapted to be reciprocated; means for moving said reciprocating shaft endwise to engage the other; means for subsequently imparting a rotary movement to said reciprocating shaft; means for moving said reciprocating shaft endwise in the opposite direction; and means for subjecting said reciprocating shaft to fluid pressure to rotate it to its normal position.

12. In a device of the class described, the combination of two normally separated alined shafts provided with means forming a temporary connection for the same, one of which shafts is adapted to be reciprocated; means for moving said reciprocating shaft endwise to engage the other; means for subsequently subjecting said reciprocating shaft to fluid pressure and thereby imparting a rotary movement to said reciprocating shaft; a spring for moving said reciprocating shaft endwise in the opposite direction; and means for subjecting said reciprocating shaft to fluid pressure to rotate it to its normal position.

13. In a device of the class described, the combination of two normally separated alined shafts provided with means forming a temporary connection for the same, one of which shafts is adapted to be reciprocated; a casing provided with two chambers connected by a fluid passage; a reciprocating piston in one of said chambers; a storage reservoir for fluid under pressure; a pipe therefrom communicating with the piston chamber; a radial blade secured to said reciprocating shaft and positioned in the other chamber; a pipe from said storage reservoir communicating with the latter chamber; and an abutment in said chamber interposed between said pipe and said passage.

14. In a device of the class described, the combination of two normally separated alined shafts provided with means forming a temporary connection for the same, one of which shafts is adapted to be reciprocated; a casing provided with two chambers connected by a fluid passage; a reciprocating piston in one of said chambers; a storage reservoir for fluid under pressure; a pipe therefrom communicating with the said piston chamber; a radial blade secured to said reciprocating shaft and positioned in the other chamber; a pipe from said storage reservoir communicating with the latter

chamber; an abutment in said chamber interposed between said pipe and said passage; and a three-way valve in each pipe between said chambers and said reservoir 5 normally open to the atmosphere and adapted to be turned to successively admit fluid pressure to opposite sides of said blade.

15. In a device of the class described, the combination of two normally separated aligned shafts provided with means adapted to temporarily connect the same, one of which shafts is adapted to be reciprocated; a casing provided with two chambers connected by a fluid passage; a storage reservoir for fluid under pressure; a pipe therefrom communicating with the chamber in which said piston is located; a radial blade

secured to said reciprocating shaft and positioned in the other chamber; a pipe from said storage reservoir communicating with the latter chamber; an abutment in said chamber interposed between the last mentioned pipe and said passage; and a three-way valve in each pipe between said chambers and said reservoir normally open to the atmosphere and adapted to be turned to successively admit fluid pressure to said piston chamber and said blade chamber.

Signed by me at 100 Boylston st., Boston, Mass., this 10th day of May, 1911.
